SNOW VEHICLE

John H. Wilkinson, R.F.D., Morgan, Utah

Filed Aug. 2, 1962, Ser. No. 71,149

Term of patent 7 years

(Cl. D14—3)

FIG. 1

FIG. 2

FIG. 3

FIG. 4

FIGURE 1 is a side elevation of a snow vehicle showing my new design.

FIGURE 2 is a front elevation of this snow vehicle.

FIGURE 3 is a rear elevation of this snow vehicle.

FIGURE 4 is a top plan view thereof.

The bottom not shown is substantially plain.

I claim:

The ornamental design for a snow vehicle, substantially as shown and described.
